UNITED STATES PATENT OFFICE

GUY MERLE YOUNG, OF MEMPHIS, TENNESSEE, ASSIGNOR OF FIFTY-TWO AND ONE-HALF PER CENT TO N. PIRANI, OF MEMPHIS, TENNESSEE

COMBINATION TOBACCO, MATCH, AND CIGARETTE PAPER CASE

Application filed June 12, 1930, Serial No. 460,674. Renewed July 5, 1932.

The present invention relates to combination tobacco cases and more particularly to a combined tobacco, match and cigarette paper case.

5 An object of this invention is to provide a handy case which is so constructed as to hold a quantity of tobacco and a supply of matches and cigarette papers.

Another object of this invention is to provide 10 a case having a plurality of compartments therein, each of the compartments holding the desired article therein against mixture with the articles in the adjoining or abutting compartments.

15 A further object of this invention is to provide a case having a relatively large tobacco compartment and a hinged match safe or compartment and in addition thereto the tobacco compartment is provided with a cigarette paper case, access to which may be had by swinging the match safe on its hinge.

The above and various other objects and advantages of this invention will in part be described in and in part be understood from 25 the following detailed description of the present preferred embodiment, the same being illustrated in the accompanying drawing wherein:—

Figure 1 is a detail front elevation of a 30 device constructed according to the preferred embodiment of this invention;

Figure 2 is a sectional view taken on the line 2—2 of Figure 1; and

Figure 3 is a sectional view taken on the 35 line 3—3 of Figure 1.

Referring to the drawing wherein like numerals of reference designate corresponding parts throughout the several views, the numeral 10 designates generally a tobacco case 40 of desired size and configuration and the numeral 11 designates a match safe or holder which is hingedly mounted as at 12 on the upper or open end of the tobacco holder 10, the match holder 11 being provided with a 45 hinged lid 13, the lid 13 having an overhanging lip or member 14 for engagement in a depression or indentation 15 provided in the outer or front wall 16 of the holder 11.

50 A cigarette paper holder generally designated as 17 comprises a relatively small cas-

ing which is secured to the inner wall of the tobacco case 10 and preferably secured to the inner surface of the front wall, the paper case 15 being open at the top thereof and the top of the case 17 is preferably substantially 55 flush with the top of the case 10 so that when the match holder 15 is in closed position, the top of the tobacco case 10 will be closed and coactively the top of the paper case 17 will be 60 closed.

The front wall of the lower case 10 is provided with an upwardly opening recess 18 and a hinged securing member 19 is adapted to substantially occupy the entire opening 18, the securing member 19 being provided with a lip 20 at the hinged edge portion thereof which is adapted to extend inwardly of the paper case 17, and the upper or free end of the closure member 19 is also provided with a locking portion 21, the locking portion 21 being preferably formed by pressing the metal of the closure member 19 outwardly or turning the edge thereof over so as to provide an outstanding ridge which is adapted to be seated in an indentation 22 which 70 is provided in a depending lip or flange 23 on the match case 11.

While it is a well known fact that cases of various kinds have been constructed for use in holding tobacco and matches, these have 80 not been so constructed as to permit the mounting of a paper receptacle therein so that all of the ingredients for the manufacture of a cigarette may be carried in a single case. Through the use of the case herein 85 disclosed, the desired quantity of tobacco 24 may be placed in the tobacco case or a receptacle 10 and a quantity of matches 25 may be positioned in the match holder 11.

Preferably, the holder 11 is of a sufficient 90 size so as to receive the conventional box of matches which are at present available for tobacco users but I, of course, do not wish to be limited to the relative size of the match case 11 as this case may be of any desired 95 size depending only upon the style, size and quantity of matches which it is desired to place therein. In the present instance, the case 11 is of a size sufficient to receive the normal box of matches in loose form.

The paper receptacle or case 17 is of a sufficient size so as to receive the normal package of cigarette papers and when the papers are mounted therein, the front portion of the package of papers is preferably torn open so as to expose the papers through the opening 18 in the front wall of the case 10. In closed position, the hinged plate member 19 is normally in alignment with the front wall of the case 10 and is placed under tension and maintained in tensioned condition by the depending flange 23 on the match receptacle 11.

When it is desired to remove the tobacco 15 24 from the case 10 the plate member 19 may be pressed inwardly by the thumb or finger thereby releasing the locking portion 21 from the indentation 22 and permitting the match safe 11 to be swung upwardly on the 20 hinge 12. When the match safe 11 has been swung upwardly, the plate 19 will be forced outwardly by the lip member 20 thereby exposing the papers 26 so that they may be moved upwardly and outwardly of the paper 25 receptacle 17.

It will be noted from the foregoing that the bottom 27 of the match safe 11 constitutes the top or lid of the tobacco case 10. When it is desired to remove the matches 30 from the match receptacle 11 the lid may be swung upwardly by forcing the locking or securing member 14 out of the indentation 15 thereby permitting the lid 13 to be swung upwardly on the hinge 28.

It will be obvious that a relatively simple and at the same time practical combination tobacco, match and paperholder or case has been provided by means of which any desired quantity of material used by the tobacco user may be carried in a convenient and compact form and that all of the ingredients used in the manufacture and consumption of cigarettes may be easily and safely carried within the case so that they will not 40 be subjected to injury or crushing in the pocket.

It is, of course, understood that various changes and modifications may be made in the details of construction and design of 50 the above specifically described embodiment of the invention without departing from the spirit thereof, such changes and modifications being restricted only by the scope of the following claims.

55 What is claimed is:—

1. A combination case of the character described comprising a tobacco case having an open upper end, a match holder hingedly mounted on said tobacco case and adapted to 60 close the open end of said tobacco case, a hinged lid for said match holder, a cigarette paper case mounted on one wall of said tobacco case and extending inwardly thereof, and a hinged plate carried by said tobacco case and adapted to hold said match holder

in closed position on said tobacco case, said plate when in opened position providing an opening in said paper case to facilitate removal of papers through the open end of the paper case.

2. A combination case of the character described comprising a tobacco receiver having an open end portion, a match holder hingedly mounted on said tobacco receiver, a hinged lid for said match holder, a paper holder mounted on said tobacco receiver, said paper holder having an open end portion flush with the open end of the tobacco receiver, said match holder when in closed position being adapted to close said tobacco receiver and said paper holder, and hinged means carried by said tobacco receiver for releasably locking said match holder on said tobacco case, said plate when in opened position providing an opening in said paper case to facilitate removal of papers through the open end of the paper case.

3. A combination case of the character described comprising a tobacco case, a paper case secured to one wall of said tobacco case and extending inwardly thereof, said tobacco case and said paper case having an open end portion, a match case hingedly secured to said tobacco case, a hinged lid for said match case, said tobacco case having an opening in one wall thereof opening outwardly of the open end of the case, a plate secured to said tobacco case and adapted to close said opening in the wall thereof, and means carried by said plate and said match case whereby to releasably secure said match case and said plate in closed position, said plate when in opened position providing an opening in said paper case to facilitate removal of papers through the open end of the paper case.

4. A combination case of the character described comprising a tobacco receiving member having one end thereof open, a match receiving member hingedly secured at one end thereof to said tobacco receiving member and adapted to close the open end of said latter member, a hinged closure member for said match receiving member, a cigarette paper case secured to said tobacco receiving member and extending inwardly of one wall thereof, said tobacco receiving member having an opening in the wall thereof communicating with said paper case, a hinged closure member for said opening, a depending lip carried by said match receiving member, said lip having an indentation on the inner face portion thereof, said closure member having a pressed out portion adapted to seat in said indentation of said lip whereby to releasably lock said match receiving member on said tobacco receiving member, and means carried by said closure member whereby to place said member under tension upon closing thereof, said plate when in opened position providing an opening in said paper case to

facilitate removal of papers through the open end of the paper case.

5. A combination case of the character described comprising a tobacco case having an open end portion, a match case hingedly mounted on said tobacco case and adapted to close the open end of said tobacco case, a hinged lid for said match case, a cigarette paper case secured to the inner 10 face of one wall of said tobacco case, said paper case having an open end portion, said open end being adapted to be closed by said match case co-actively with the closing of the open end of said tobacco case, said 15 tobacco case having an opening in one wall thereof whereby to permit access from the side to said paper case, a hinged closure member for said opening, means carried by said closure member and said match case whereby 20 to releasably lock said match case in closed position, and a lip carried by the hinged end of said closure member and adapted to engage the wall of said tobacco case whereby to place said closure member under tension 25 upon closing thereof, said plate when in opened position providing an opening in said paper case to facilitate removal of papers through the open end of the paper case.

In testimony whereof I hereunto affix my 20 signature.

GUY MERLE YOUNG.
